US00D616384S

(12) **United States Design Patent**
Chan et al.

(10) **Patent No.:** US D616,384 S
(45) **Date of Patent:** ** May 25, 2010

(54) **LED MODULE**

(75) Inventors: **Shih Hsiung Chan**, Hsinchu County (TW); **Jian Shihh Tsang**, Taipei County (TW); **Chih Chiang Huang**, Hsinchu (TW)

(73) Assignee: **Advanced Optoelectronic Technology, Inc.**, Hsinchu Hsien (TW)

(**) Term: **14 Years**

(21) Appl. No.: **29/332,943**

(22) Filed: **Feb. 27, 2009**

(30) **Foreign Application Priority Data**

Feb. 29, 2008 (TW) 97301085

(51) LOC (9) Cl. **13-03**

(52) U.S. Cl. **D13/180**

(57) **CLAIM**

The ornamental design for an LED module, as shown and described.

DESCRIPTION

FIG. 1 is a front view showing our new design for an LED module;

FIG. 2 is a rear view of the LED module of FIG. 1;

FIG. 3 is a top plan view of the LED module of FIG. 1;

FIG. 4 is a bottom plan view of the LED module of FIG. 1;

FIG. 5 is a left side view of the LED module of FIG. 1;

FIG. 6 is a right side view of the LED module of FIG. 1; and, FIG. 7 is a perspective view of the LED module of FIG. 1.

The LED module is shown broken away in FIGS. 1–7 of the drawing to indicated indeterminate length, it being understood that it has a uniform shape and appearance through its length.
